IRA E. McCABE, OF CHICAGO, ILLINOIS

ELECTRIC SWITCH OF THE MERCURY TUBE TYPE

Original application filed July 4, 1928, Serial No. 290,287. Divided and this application filed November 24, 1930. Serial No. 497,848.

This invention relates to improvements in electric switches of the mercury tube type in which there is a mercury to mercury make and break and this application is a division 5 of Serial No. 290,287, filed July 4, 1928, and is a continuation or further development of the invention disclosed in applicant's prior Patent No. 1,757,436, dated May 6, 1930.

It is an object of this invention to isolate 10 one of the terminals of the switch in a cup of insulating material adapted to contain a small body of mercury with the other terminal acting as a support for the cup and always in contact with the main body of mercury in a mercury tube switch, so that when the tube is operated in one direction the main body of mercury will overflow the sides of the isolating cup, make an electrical contact with the mercury contained therein and 15 through the contained mercury to the isolated terminal and when operated in the opposite direction will flow away from said cup and break the electrical contact through the small body of mercury that remains in the cup and 20 thereby break the circuit through the switch.

While the preferred forms of this invention, as applied to particular forms of mercury tube switches, are illustrated upon the accompanying sheet of drawing, it is to be understood that minor detail changes may 25 be made without departing from the scope thereof.

In the drawing:

Figure 1 is a view in central vertical section, with parts shown in side elevation of 30 an embodiment of this invention to a magnetically operated mercury tube switch.

Figure 2 is a similar view of another application of this invention to the type of mercury tube switch shown in Figure 1.

Figure 3 is a view similar to Figures 1 and 2 illustrating this invention applied to another form of the same general type of switch.

Figures 1, 2 and 3 illustrate the application

of this invention to a form of mercury tube switch in which the tube is arranged in a vertical position with the terminals supported within a cylinder of magnetic material in engagement with the main body of the mercury 50 which is raised or lowered, as the case may be, by a magnet surrounding the tube to change the level of the main body of mercury to make or break the circuit.

In Figure 1, the tube 1 is held in a vertical position, as shown, with the lead in wires or terminals 2 and 3 sealed in spaced apart relation in the thickened upper end 4 of the tube. A cylinder 5 of magnetic material is arranged within the tube floating upon the 55 main body 6 of the mercury contained therein. The cup 7, constructed of insulating material having outwardly flaring lips above a circumferential groove and adapted to contain a small body of mercury, is held by 60 the lead in wire 2, as shown, above the normal level of the main body 6 of the mercury with the other lead in wire 3 terminating within the small body 8 of the mercury contained within the cup 7. An electro-magnet 65 70 75 80 85 90 95 99 is arranged about the lower end of the tube 1 which when energized will draw the magnetic cylinder 5 downward within the main body of the mercury causing its level to ascend and submerge the cup 7 whereby an electrical connection is made between the lead in wires or terminals 2 and 3, when the main body 6 engages the small body 8 of mercury. When the magnet 9 is deenergized the magnet cylinder 5 is released and will ascend until it again floats in the main body of the mercury causing its level to descend and break the connection. It is preferable to provide the bottom of the cylinder 5 with shock absorbers, such as springs 10, to prevent the breaking of the tube when the magnet 9 is energized. It is also obvious that a permanent magnet may be substituted for the electro-magnet which may be mechanically moved up and down about the tube 1 to cause 90

the magnetic cylinder 5 to make or break the circuit.

In Figure 2, both ends of the tube 1 are thickened, the upper end 4 sealing spaced apart lead in wires 11, both of which terminate in the small body of mercury contained within the cup 7, which is supported by one of the lead in wires 12 sealed in the lower end 13 of the tube, the other of which terminates within the main body 6 of the mercury in the tube 1. The lead in wire 12 supports the cup above the normal surface of the main body of mercury and the magnetic cylinder 5 is operated to vary the level of this mercury to make and break the circuit in the same manner as described above in relation to Figure 1. In this form the switch may be employed in a high amperage circuit, the passage of which through the customary single lead in wires would heat the same to a degree that would endanger the glass seal thereabout.

In Figure 3, the normal operation of the switch is reversed. The tube 1 is so formed to be of less vertical length by forming the upper portion reentering the main body of the tube, as shown, with space between the walls of both portions to allow the magnetic cylinder 5 to pass up and down therebetween. In this form the thickened upper end 4 seals and supports the lead in wires 2 and 3 with the lead in wire 2 supporting the cup 7 normally submerged within the main body 6 of the mercury within the tube and the lead in wire 3 terminating within the small body of mercury contained in the cup. The magnetic cylinder 5 normally floats upon the main body 6 of the mercury with its lower portion submerged therein causing the level of the mercury to normally be above the cup 7. The electro-magnet 9 in this type is arranged about the upper portion of the tube 1 and the parts are so proportioned that upon energizing of the magnet the magnetic cylinder will be drawn upward out of the main body of the mercury whereby its level will descend below the bottom of the cup 7, as shown, and thereby break the circuit through the switch. When the electro-magnet is deenergized the magnetic cylinder will be released and enter the main body of mercury which will be caused to rise thereby and submerge the cup and again close the circuit through the switch.

55. What I claim is:

1. An electric mercury tube switch comprising a vertical sealed tube, a main body of mercury contained therein, a member of magnetic material normally floating thereupon, lead in wires sealed in an end of the tube and extending therein, one supporting a cup of insulating material normally containing a small body of mercury therein above the normal level of the main body of mercury and another terminating within said small

body of mercury within said cup, and a magnet adapted when energized to draw the magnetic member within the main body of mercury causing the mercury to rise in the tube, submerge the said cup and close the circuit between the respective lead in wires and when deenergized to release the member to emerge from the main body of mercury whereby the level of the mercury will descend below the cup and break the circuit between the said lead in wires. 75

2. An electric mercury tube switch comprising a vertical sealed tube, a main body of mercury contained therein, a body of magnetic material normally floating thereupon, a cup of insulating material normally containing a small body of mercury supported above the normal level of the main body of mercury independently of the magnetic member, a plurality of lead in wires sealed in each end of the tube, whereby a circuit of greater amperage than can be carried by a single lead in wire without danger to the seal is distributed, one set of lead in wires passing through the main body of mercury and exteriorly supporting the said cup with the other set terminating in the small body of mercury within said cup, and a magnet adapted to draw the magnetic member within the main body of mercury causing it to rise and engage the mercury within the said cup and thereby close the circuit. 85

3. An electric mercury tube switch comprising a vertical sealed tube having its upper portion bent back upon itself to reenter the main body with a clearance between the respective side walls, a cylinder of magnetic material adapted to travel within said clearance, an electro-magnet adapted when energized to raise and hold the said cylinder at its upper limit of travel, a main body of mercury within the tube having its normal level adjacent the lower end of said cylinder when in its uppermost position, lead in wires sealed in the re-entrant end of the tube, one embracing and angularly supporting a cup of insulating material normally containing a small body of mercury above the normal level of the main body and the other terminating within the mercury contained in said cup, whereby the switch circuit is broken between the respective lead in wires, said cylinder adapted when the magnet is deenergized to drop into the main body of the mercury and cause the level of the mercury to rise until the cup is submerged therein and thereby close the circuit between the respective lead in wires. 100

4. An electric mercury tube switch including a vertical sealed container, a main body of mercury contained therein, a plurality of electrodes extending through and sealed in the container walls, a cup of insulating material containing a small body of mercury embraced and supported by one of the elec- 110

trodes above the normal level of the main body of mercury to receive the end of a complementary electrode submerged in the mercury within the cup and insulated from the other electrode, a freely moving member of magnetic material mounted within the container, and an exterior magnet adapted to impart movement to the magnetic member to cause the main body of the mercury to overflow the cup and contact with the small body of mercury contained therein to close the circuit between the complementary electrodes.
